UNITED STATES PATENT OFFICE.

EDDY R. WHITNEY, OF PHILADELPHIA, PENNSYLVANIA, ASSIGNOR TO COMMERCIAL TRUCK COMPANY OF AMERICA, OF PHILADELPHIA, PENNSYLVANIA, A CORPORATION OF PENNSYLVANIA.

DRIVING MECHANISM.

1,149,106.

Specification of Letters Patent. Patented Aug. 3, 1915.

Original application filed June 4, 1912. Serial No. 701,605. Divided and this application filed April 24, 1913. Serial No. 763,427.

To all whom it may concern:

Be it known that I, Eddy R. Whitney, a citizen of the United States, residing in Philadelphia, Pennsylvania, have invented 5 certain Improvements in Driving Mechanism, (being a division of my application for patent filed June 4, 1912, Serial No. 701,605,) of which the following is a specification.

10 One object of my invention is to provide a novel combination of driving mechanism and inclosing structure particularly adapted for use between a driving motor and a driven wheel, the arrangement and construction of parts being such that the said mechanism is completely inclosed so as to be dust proof.

It is further desired to provide a novel 20 form of inclosing casing and wheel supporting structure particularly designed to house certain gearing, the arrangement of parts being such that there is no sliding joint between two or more parts of the casing through which dust might gain access to the 25 mechanism in the interior thereof.

It is further desired to provide mechanism 30 having the above noted characteristics which shall be relatively simple, compact and substantial.

30 These objects and other advantageous ends I secure as hereinafter set forth, reference being had to the accompanying drawings, in which:—

Figure 1 is an elevation partly in section, illustrating my invention as constructed to transmit power from a motor to the axle driven thereby; Fig. 2 is a section on the line *a*—*a*, Fig. 1; Fig. 3 is a side elevation, partly in section, illustrating a slightly 40 modified form of my invention; Fig. 4 is a vertical section on the line *b*—*b*, Fig. 3, and Fig. 5 is a vertical section of another form of my invention.

In Figs. 1 and 2 of the above drawings, I 45 have illustrated an electric motor having a casing 2 closed at one end by a head 3. Said motor also has an armature shaft 4 carried at the end thereof distant from the head 3 by a bearing 5, and at the opposite 50 end extended through said head so as to carry outside of it a pinion 6 and a grooved bearing wheel or roller 7. Said pinion and roller are preferably integral and it is to be

noted that the diameters of the bottom of the groove of the said roller and of the pitch 55 circle of the pinion are the same. The motor head 3 has in its outer face a cylindrical depression or recess whose curved surface is designed to receive three or more rollers 8, each of which forms part of a gear 9 and 60 engages the roller 7 on the armature shaft 4 so as to support the same. The motor head 3 is held to the motor casing 2 in the present instance by screws of which one is shown at 10, and there is bolted to said head 65 a second casing 11 providing a bearing 12 for a shaft 13, concentric with the armature shaft 4. That portion of the said shaft 13 projecting outside of the bearing has in this instance a tapered part 14 and a threaded 70 extremity 15 for a nut. Inside the casing 11 the axle or driven shaft 13 has three integral arms 16 each carrying at its outer end a fixed stud or spindle 17 on which is rotatably mounted one of the gears 9, and in addition there is fixedly mounted within the casing 11, an internally toothed gear 18, in 75 position to be engaged by the various gears 9, which before noted also engage the armature pinion 6. This internal gear is so proportioned that its pitch circle has the same diameter as that of the cylindrical bearing 19 of the head 3. Under operating conditions the turning of the armature shaft 4 under the action of the motor drives the pinion 6 and roller 7, thereby causing the gears 9 to roll upon the internal gear 18 and through arms 16 rotating the shaft 13 with the member which may be connected to it. With this arrangement it will be noted that 80 the pinion carrying end of the armature shaft is supported through the rollers 8 of the gears 9 on the curved bearing surface 19 of the motor head, which with the rollers 8 and 7 is suitably hardened or made of hard 85 material to reduce the wear to a minimum. Owing to the grooved form of the rollers 7 and to the corresponding form of the rollers 8, transverse motion of the gears 9 relative to the gear 18 is effectually prevented and 90 said rollers are also retained in their proper positions relatively to the curved bearing surface 19; it being noted that under normal conditions the sides of the groove in said roller 7 do not engage the sides of the 95 rollers 8. With this construction, the fri-

tional loss between the various parts is reduced to a minimum, since the bearing surface 19 of the head 3 has the same diameter as the pitch circle of the internal gear 18, 5 while the diameters of the rollers 8 are the same as that of the pitch circles of the gears 9.

In some instances, I may arrange the parts as shown in Figs. 3 and 4, in which case the 10 motor head 3^a has a bearing 20 for the pinion end of the armature shaft 4^a. Said motor head as before, is provided with a recess providing a cylindrical bearing surface 19 engaged by rollers 8^a formed integral with the gears 9, which as before, are carried on studs 17^a projecting from arms 16^a formed integral with or connected to a rotary shaft 13^a. In this case, however, each of the studs or spindles 17^a has mounted on 20 it a second gear 21, formed integral with a gear 9 and a roller 8^a; the arrangement being such that said gears 21 roll on the internally toothed gear 18^a, which as before is mounted within a casing 11^a and attached 25 to the motor casing in any suitable manner. Said casing however, is provided with a tubular extension fitting into the hub 22 of the wheel 23 and the shaft 13^a, which extends loosely through this tubular extension 24, is connected with the hub so as to 30 turn the same by means of a hub cap 25 and coupling ring 26. Two sets of roller bearings 27 and 28 are mounted between the casing extension 24 and the wheel hub, and the 35 wheel and motor structures are connected to the frame of the vehicle through a spring structure 29 which engages the top part of the casing 11^a. With this arrangement of parts, the revolution of the armature shaft 40 4^a turns the gears 9 and causes the gears 21 attached thereto to roll around upon the internal gear 18^a whose pitch circle has the same diameter as the bearing surface 19 of the motor head 3^a;—the rolls 8^a being the 45 same in diameter as the pitch circle of the said gears 21. The armed structure or spindle 16^a is thus rotated, turning the shaft 13 and through the hub cap 25 and coupling 26 causing the wheel hub 22 and with it the 50 wheel 23, to turn on the fixed structure provided by the tubular extension 24 of the casing 11^a.

While the bearing surface 19 in the recess of the head 3 is properly cylindrical in form and of the same diameter as the pitch circle 55 of the internal gear, it is obviously possible to make it more or less conical or of a curved section without departing from my invention.

In that form of my invention shown in 60 Fig. 5, I have shown a combination of apparatus in which the end of the armature shaft adjacent the gearing is supported by the latter in the manner illustrated in Figs. 1 and 2, although the motor casing, as in 65 Fig. 3, is provided with a hollow projection 24^a adapted to form a hollow wheel axle.

I claim:—

1. The combination of a casing including a head closing the same and having a roller 70 bearing surface; an internally toothed gear fixed within said casing; with mechanism coöperating with said gear and including a roller operative on said bearing surface.

2. The combination of a gear casing including a head closing the same and having a cylindrical bearing surface; an internally toothed gear fixed within said casing in such position that its pitch line has the same diameter as said bearing surface; with 80 mechanism coöperating with said gear and the bearing surface.

3. The combination of a gear casing including a removable head having a roller bearing surface; and an internally toothed 85 gear mounted within the casing having its pitch line in the cylindrical surface, including the roller bearing surface, with mechanism coöperating with said gear and bearing surface.

4. The combination of a gear casing having a supporting journal; an internally toothed gear fixed within the casing concentric with the center line of the journal; and a roller bearing surface also within the 95 casing concentric with said gear.

In testimony whereof, I have signed my name to this specification, in the presence of two subscribing witnesses.

EDDY R. WHITNEY.
